UNITED STATES PATENT OFFICE.

BURT E. LLOYD, OF WEST HOBOKEN, NEW JERSEY.

VOICE FOR TOYS.

1,282,702.

Specification of Letters Patent. Patented Oct. 22, 1918.

Application filed December 7, 1917, Serial No. 206,060. Renewed September 18, 1918. Serial No. 254,677.

To all whom it may concern:

Be it known that I, BURT E. LLOYD, a subject of the King of Great Britain, and a resident of West Hoboken, in the county of 5 Hudson and State of New Jersey, have invented a new and Improved Voice for Toys, of which the following is a full, clear, and exact description.

This invention relates to a sound device 10 for toys, and relates more particularly to improvements in a "ma-ma" voice or other device in which a compressible element is employed for forcing air through a reed for the production of sound.

15 The invention has for its general objects to improve and simplify the construction of devices of this character so as to be reliable and efficient in use, comparatively easy to manufacture, and of durable and substantial design.

20 A more specific object of the invention is the provision of a novel construction which embodies a hollow, flexible hemisphere or half of a rubber ball which forms part of 25 the air-compressing box or bellows.

Still another object of the invention is to provide a novel arrangement of air-compressing or pump box and sound box, the 30 reed being set in an opening in a wall between the boxes.

With such objects in view, and others which will appear as the description proceeds, the invention comprises various novel features of construction and arrangement of 35 parts which will be set forth with particularity in the following description and claims appended hereto.

In the accompanying drawing, which 40 illustrates certain embodiments of the invention and wherein similar characters of reference indicate corresponding parts in all the views,

Figure 1 is a side view of the device;

45 Figs. 2 and 3 are opposite end views thereof;

Fig. 4 is a central longitudinal section;

Fig. 5 is a central longitudinal section of a modified form of sound-producing device;

Fig. 6 is a side view thereof; and

50 Fig. 7 is an end view.

Referring to the drawing, 1 designates a cylindrical body which is preferably a piece of mailing tube stock and into one end thereof is set a ring 2 of the same material, 55 and fitted around the portion of the ring 2

that projects out of the casing 1 is a half section 3 of a rubber ball. The parts 1, 2 and 3 are glued together so as to be permanently attached, and fitted and glued in the ring 2 is a disk 4 which co-operates with the 60 ring and rubber hemispherical diaphragm 3 to constitute an air-compressing or pump box 5. A reed 6 is set into an opening 7 in the disk and glued at such opening so as to be permanently attached. The air forced 65 through the reed causes the lip 8 to produce a sound. On the disk 4 is glued a short ring 9 in which is fitted and glued a disk 10 whereby the ring 9 and disk 10 co-operate with the wall 4 to form a sound-box 11. For 70 articulating the sound an opening or mouth 12 is formed in the disk 9, and around this mouth is a rubber lip 13, and through this lip pass valve disks 14 and 15 carried by a stem 16 which passes through the diaphragm 75 3 and carries a button or knob 17 on its outer end. Normally the parts are in the position shown in Fig. 4, and when the diaphragm 3 is compressed air is forced through the reed 6 and the sounds are articulated by the valve disks 14 and 15 successively passing through the lip 13. Surrounding the cylinder 1 is an outer cylinder 18, which is of mailing tube stock, and which is of such length as to circumferentially embrace the edge of the hemispherical diaphragm 3 to assist in keeping the diaphragm 80 attached to the body of the device. This outer cylinder 18 is loose from the body of the device and is adapted to be set into a 85 stuffed body of a doll to form a chamber into which the device can be fitted, and when the device is fitted into the outer casing 18 the latter embraces the edge of the diaphragm 3 and assists in holding it effectively in place.

In the construction shown in Figs. 5 to 7 an unarticulated sound is produced since no valves and lip are employed. The sound box is made up of a ring 19, hemispherical diaphragm 20 and disk 21, the ring 19 being fitted in a cylindrical casing 22. Co-operating with the disk 21 is a second disk 23 fitted in the casing 22 to co-operate with the casing and disk 21 to form a sound box 24. In the 105 disk 21 is a reed 25. By compressing the diaphragm 20 air is forced through the reed, whereby a sound is produced which passes out from the sound box through an opening 26 in the disk 23.

From the foregoing description taken in connection with the accompanying drawing, the advantages of the construction and method of operation will be readily understood by those skilled in the art to which the invention appertains, and while I have described the principle of operation, together with the device which I now consider to be the best embodiment thereof, I desire to have it understood that the device shown is merely illustrative and that such changes may be made when desired as fall within the scope of the appended claims.

Having thus described my invention, I claim as new and desire to secure by Letters Patent:

1. A sound producing device for toys, including a hemispherical resilient diaphragm, a tubular member fitted into the open side of the diaphragm, and another tubular member fitting around the first, with its edge set in from the inner edge of the first-mentioned member, whereby the edge of the second-mentioned member forms a shoulder for receiving the edge of the diaphragm.

2. A sound producing device comprising a hemispherical resilient diaphragm, and a body having a reduced end fitting into the open side of the diaphragm and formed with an annular shoulder on which the edge of the diaphragm bears.

3. In a sound producing device, the combination of a casing, a ring fitted therein and projecting from the casing to form a shoulder, and a hemispherical, resilient diaphragm fastened to the shoulder, with an outer casing removably fitting around the

first-mentioned casing and embracing the edge of the diaphragm.

4. A sound producing device comprising a body having a circumferential shoulder, a hemispherical, flexible diaphragm, a wall extending across the body to coöperate with the diaphragm to form a pump chamber, and a reed in the wall of the pump chamber.

5. A device of the class described comprising a casing, a ring of uniform diameter fitted in the casing and projecting partly therefrom, a diaphragm having its edge fastened to the edge of the casing and to the projecting part of the ring, and means in the casing for producing a sound when the diaphragm is compressed.

6. A device of the class described comprising a casing, a ring fitted in the casing and projecting partly therefrom, a diaphragm having its edge fastened to the edge of the casing and to the projecting part of the ring, a disk fitted in the ring, a reed carried by the disk, and a sound box at the side of the disk opposite from the diaphragm and having an opening through which sound is emitted.

7. A device of the class described including a chamber having a flexible portion arranged to be actuated for causing air to flow into and out of the chamber, one wall of the chamber being provided with an opening, and a reed fastened in the opening, the said reed being in the form of a channeled body open at its ends, and a vibratory member at the inner end of the body and within the chamber.

BURT E. LLOYD.
